UNITED STATES PATENT OFFICE.

JERRY A. LAWRENCE, OF BRACKENRIDGE, PENNSYLVANIA, ASSIGNOR TO HARRY E. SHELDON, OF PITTSBURGH, PENNSYLVANIA.

ANNEALING-BOX.

1,080,115.

Specification of Letters Patent. Patented Dec. 2, 1913.

Application filed December 13, 1912. Serial No. 736,476.

To all whom it may concern:

Be it known that I, JERRY A. LAWRENCE, a citizen of the United States, residing at Brackenridge, in the county of Allegheny and State of Pennsylvania, have invented new and useful Improvements in Annealing-Boxes, of which the following is a specification.

My invention relates to annealing boxes and has particular reference to roofs therefor.

It is the object of my invention to strengthen the roofs of annealing boxes by making the roofs double, and connecting the roofs together so as to support each other. The roofs of annealing boxes are very liable to sag by their own weight under the softening action of the intense soaking heat, to which they are subjected in annealing furnaces.

Referring to the accompanying drawings, Figure 1 is a side view of the preferred form of annealing box with my improvements shown in dotted lines; Fig. 2, a vertical section of Fig. 1; and Fig. 3, a plan view of Fig. 1.

On the drawing, 1 represents the sides of the annealing box, 2 the ends thereof, and 3 the roof as a whole. The sides 1 are strengthened by vertical ribs or rails 4 of steel cast therein or slid down in grooves therein. The top member 5 of the roof is arched from the top of one side to the top of the other side. I have shown this member conforming to an arc drawn from the center, marked 6, midway between the sides 1. The lower member 7 of the roof also arched from one side of the annealing box to the other, conforms to an arc having the same radius as the member 5, but having its center 8 sufficiently below the center 6 to space the roof members 5 and 7 apart the desired distance. The roof-members are connected together by the spacers 9 preferably cast integrally with the said members. These spacers are preferably staggered or arranged in diagonal rows.

In order that the sand core may be removed between the roof-members, I provide the lower member with a suitable number of 50 openings 10, which also serve to equalize the temperature and pressure between the main chamber of the annealing box and the chamber between the roof-members.

It is seen that the roof-members mutually support each other by means of the spacers 9. The lower roof-member is shielded from the direct attack of the furnace heat and assists to prevent the upper roof-member from sagging, this member being 60 exposed directly to the heat of the furnace.

I claim—

1. In an annealing box, a top composed of two spaced roofs, one above the other, the roofs being rigidly connected with the sides, 65 and means rigidly connected to the two roofs for spacing them apart and connecting them together at a plurality of places between the sides.

2. In an annealing box, a top composed 70 of two spaced roofs, one above the other, the roofs being rigidly connected with the sides, and means rigidly connected to the two roofs for spacing them apart and connecting them together, one of the roofs having openings connecting the space between the roofs with the interior of the box.

3. In an annealing box, a top composed of two spaced roofs, one above the other, and means for rigidly connecting one roof 80 to the other at a plurality of places between the sides.

4. In an annealing box, a roof composed of two spaced members, one above the other, the lower member having openings connecting the interior of the box with the space between the spaced members.

Signed at Pittsburgh, Pa., this 9th day of December, 1912.

JERRY A. LAWRENCE.
